REINFORCED CONCRETE STRUCTURE

John M. Crom, Washington, D. C., assignor to
Preload Enterprises, Inc., a corporation of
Delaware

Application May 1, 1946, Serial No. 666,403

2 Claims. (Cl. 138—84)

1. This invention relates to reinforced concrete structures and more particularly to reinforced cylindrical concrete structures of the nature of reinforced concrete pipe sections, reinforced concrete tank sections and other reinforced concrete constructions of a generally cylindrical shape.

Prior to this invention, cylindrical concrete structures have been reinforced by steel members extending either longitudinally, circumferentially or both. In some cases these reinforcing members have been placed under stress so that they tend to exert a compressive force on the concrete and thereby more effectively prevent its cracking or breaking.

Since cylindrical concrete structures are usually subjected both to radial stresses and to longitudinal stresses, it has heretofore been necessary in order to reinforce the concrete structures against both these stresses to incorporate in such structures both longitudinally extending and circumferentially extending reinforcing members.

In accordance with the principles of this invention, it has been found possible to incorporate in cylindrical concrete structures a single type of reinforcing, which reinforcing adequately reinforces the cylindrical concrete structures against both radial and longitudinal stresses.

Briefly, the present invention comprises the reinforcing of concrete structures of generally cylindrical shape by the incorporation therein of a basket or double-helically wound reinforcing material so positioned as to provide both longitudinal and radial strength. Preferably, the reinforcing material is steel wire and is wound onto the cylindrical concrete structure at such an angle that it provides the desired ratio between longitudinal reinforcing and radial reinforcing. For example, if a reinforcing wire were wound onto the cylindrical concrete object so that there was no appreciable angle between the wire and a plane normal to the longitudinal axis of the concrete structure, the wire would provide radial support or reinforcement, but would provide substantially no longitudinal reinforcement. Similarly, if the wire were placed in the concrete structure in a direction parallel to the longitudinal axis thereof, it would provide longitudinal reinforcement, but substantially no radial reinforcement. It has been found, for most purposes, that if the wire is wound on the concrete structure at an angle of approximately 20° to a plane normal to the longitudinal axis, it will provide the proper distribution between longitudinal and radial reinforcement.

The present invention further contemplates the

application of the reinforcing material in a pretensioned state, that is, it contemplates that the wire or other reinforcing material shall be wound onto the concrete structure under a predetermined tension and will thereby provide more efficient and more satisfactory reinforcement. This invention further contemplates the covering of the reinforcing material, once it is in place on the concrete structure, with a coating or covering of some protective material such as additional concrete or asphalt. In some instances it may be found desirable to coat the reinforcing material itself with asphalt or some similar material prior to its application to the pipe so that it will be free to move slightly with relation to the pipe and thus equalize the tension at various points on the surface of the cylindrical structure.

Further details and advantages of this invention may be ascertained from a consideration of the appended drawings and the following detailed description of the preferred embodiment of this invention as illustrated and described therein.

In the drawings:

Figure 1 is a side elevational view, partly in section, of a piece of concrete pipe constructed in accordance with the principles of this invention;

Figure 2 is a detail view on a somewhat larger scale of a part of the concrete pipe of Figure 1; and

Figure 3 is a cross-sectional view taken on lines 3—3 of Figure 2.

As illustrated in Figure 1, a concrete pipe section may comprise an elongated cylindrical portion 10 with a collar 11 integrally formed at one end thereof for the purpose of attaching the pipe section to an adjacent section. Such a pipe section, in accordance with the principles of this invention, may comprise a concrete pipe base 12 wound with a steel reinforcing wire 13 and covered by an outer coating 14 of concrete or some other material.

The reinforcing wire 13 may be wound on the pipe in the form of a continuous double helix in which the wire progresses continuously around the pipe and at the same time continuously from the top and the bottom of the pipe and back again. By starting at the bottom of the pipe at an arbitrary point, which may be designated as 15, and proceeding to wind the wire around and up the pipe to the top and then continuing to wind the wire around and down the pipe back to the bottom, and then repeating this process until the pipe is completely covered by a series of double helices of wire, it has been found that a

very effective reinforcing both longitudinally and radially may be accomplished.

The reinforcing wire 13 may be suitably anchored in any desired manner at the beginning and end of its winding and at each of the points at the top and bottom of the pipe where it changes direction. The collar 11 may be separately wound in a radial direction by reinforcing wire 16 and additional reinforcing members (not shown) may be arranged to extend from the 10 collar 11 into the upper part of the pipe section 14 to provide the necessary reinforcing in the collar 11 and throughout the area where the collar 11 joins the pipe section 14.

Preferably, a predetermined amount of tension 15 is applied to the reinforcing wire 13 and also to the reinforcing wire 16 during its application to the pipe and, if desired, asphalt or the like may be applied to the reinforcing wire to give it a certain freedom of movement with respect to the 20 pipe.

In most cases, it will be found desirable to cover the reinforcing wire with an additional coating of concrete or asphalt or some other material 14 so as to protect the reinforcing wire from exposure to the elements.

A particularly desirable manner of anchoring the reinforcing wire 13 in the places where it changes direction at the top and bottom of the pipe is illustrated in Figures 2 and 3. The concrete pipe base 12 is usually precast and it is relatively simple in the process of precasting this concrete type base to cast thereon a series of lugs 17 at the time the pipe is cast. These lugs may be of almost any desired shape but preferably are of the shape shown in Figures 2 and 3 so that they expediently catch and hold the reinforcing wire 13 as it reaches the end of its lateral travel and reverses its direction.

With such lugs cast on the concrete pipe base 40 12, the reinforcing wire 13 may be rather easily wound onto the pipe base by either placing the pipe on a rotating standard and feeding the wire onto the pipe while rotating the pipe, or rotating the wire applying device around the pipe while the pipe itself is held stationary. During the application of the wire, it is, of course, necessary to move either the pipe or the wire applying means in a longitudinal direction with respect to

5 the pipe. By properly coordinating the longitudinal motion and the rotational motion, the wire may be wound onto the pipe at any desired angle. An angle of 20° to a plane perpendicular to the longitudinal axis of the pipe has been found satisfactory for most purposes, but this can be varied as desired for any particular concrete structure. In most cases, however, an angle of between 15° and 30° will be found satisfactory and angles outside of this range will be found to provide a less desirable distribution of the reinforcement.

What is claimed is:

1. A radially and axially reinforced hollow cylindrical concrete structure adapted to withstand internal pressure that comprises a hollow cylindrical concrete base member, a prestressed reinforcing material wound onto the outer surface thereof and forming a series of helices thereon, some of which helices slope in one direction and some of which slope in the opposite direction, and a concrete coating covering said reinforcing material.

2. A radially and axially reinforced, hollow, cylindrical, concrete structure adapted to withstand internal pressure, that comprises a hollow, cylindrical, concrete base member, a prestressed reinforcing material forming a series of helices on the outer surface thereof, some of which helices slope in one direction at an angle of between 15° and 30° to a plane perpendicular to the longitudinal axis of the structure, and some of which slope in the opposite direction at substantially the same angle.
